UNITED STATES PATENT OFFICE.

ERROL B. SHAND, OF PITTSBURGH, PENNSYLVANIA, ASSIGNOR TO WESTINGHOUSE ELECTRIC & MANUFACTURING COMPANY, A CORPORATION OF PENNSYLVANIA.

MERCURY-PUMP SYSTEM.

Application filed August 3, 1927. Serial No. 210,239.

My invention relates to vacuum pumping systems and it has particular relation to such systems as applied to metal-tank mercury-arc rectifiers.

5 The principal object of my invention is to provide means for controlling the action of the high-vacuum mercury-vapor pump and a motor-operated valve which connects said pump to the rectifier tank to be evacuated.

10 A more particular object of my invention is to provide a novel valve-operating mechanism for providing a rapid closure of the valve, when occasion demands, and a more leisurely opening thereof at proper times.

15 A further object of my invention is to provide a novel thermostatic control means associated with the mercury-vapor pump for opening and closing the valve of the above-described combination at the proper times.

20 A still further object of my invention is to provide a novel water-flow relay which is associated with the cooling circuit of the mercury-vapor pump for controlling the heating circuit thereof, so that the heating circuit 25 may be energized only when the proper amount of cooling water is being circulated.

With the foregoing and other objects in view, which will be understood from the following description and claims, my invention 30 consists in the combinations and details of structure herein described and claimed and illustrated in the accompanying drawing, wherein

Figure 1 is a curve chart illustrating the 35 conditions in the water-flow meter,

Fig. 2 is a partially diagrammatic cross-sectional view illustrating the entire assembly and the electrical circuits associated therewith,

40 Fig. 3 is a curve chart referring to the operation of the thermostatic device on the mercury-vapor pump,

Fig. 4 is an elevational view of a part of the valve-operating mechanism, and

45 Fig. 5 is a plan view, partially in section, illustrating the worm shaft and its connection to the motor shaft.

As shown in Fig. 2, my invention is preferably applied to a metal-tank rectifier 7, 50 which is shown on a somewhat reduced scale, as compared to the scale on which the other parts of the apparatus are drawn. The rectifier tank 7 is provided with an exhausting pipe 8 which is coupled to a valve 9 such as shown and described in my copending appli-

cation, Serial No. 141,783, filed October 15, 1926, and issued November 27, 1928, as Patent 1,693,407. The valve is of the moving-diaphragm type, having a diaphragm 10 to which is secured a valve seat 11 and a valve 60 stem 12.

The valve 9 is connected, in turn, to a mercury-vapor pump 13 of any desired construction, having an exhaust port 14 which is connected to an interstage reservoir and rotary pump, neither of which is illustrated, as any known or preferred form of apparatus may be utilized for the purpose. The mercury pump 13 is provided with a water jacket 15 having an inlet port 16 in which is located a 65 feeding valve 17 for controlling the water-flow to a predetermined restricted amount and pressure, a suitable source of water supply (not shown) being connected to the inlet pipe 16.

In the discharge pipe 18 for the water, as it leaves the jacket surrounding the pump, is provided a water meter 20, or mechanism for responding to pressures which are developed as a result of the flow of water therethrough. The water meter 20 is shown somewhat diagrammatically in Fig. 2 for simplicity of illustration, but the essential features of the mechanism are well illustrated. The device consists of a pressure chamber 21, 80 one wall of which consists of a movable diaphragm or bellows 22, to which is connected the stem 23 of an electrical switch mechanism 24, for a purpose hereinafter described. The pressure chamber 21 is in direct communication with an inlet port 25 of the water meter and is in communication with an outlet port 26 by means of a restricted orifice 27.

In the operation of the cooling-water mechanism, it will be understood that a relatively high-pressure source of water supply is connected to the intake pipe 16, wherein the water pressure may be as much as 50 pounds per square inch, or more. A restricted amount of water is circulated through the 95 cooler, as controlled by the feeding valve 17, leaving through the meter 20, the outlet port 26 and the discharge pipe 18. The restricted water flow, passing through the water meter 20, develops a relatively small pressure in the pressure chamber 21 of the meter, which forces out the diaphragm 22 against the action of a spring 28.

In order to make the water-flow meter 20 as delicate as possible, so that it will respond 100

very accurately to small pressures developed in the pressure chamber 21, it is necessary to provide means for preventing damage to the diaphragm as a result of excessive pressures which would be developed in case the pressure reducing feeding valve 17 were turned on full. I have therefore provided a by-pass opening 29 between the pressure chamber 21 and the outlet passage 26 of the meter, said opening being normally closed by means of a plug or closure member 30 depending from the diaphragm 22. When a certain predetermined pressure is developed against the diaphragm 22, the switch contacts 24 are closed, and at, or just beyond, this pressure, the plunger 30 comes out of the opening 29, thereby providing a relatively unrestricted flow of water through the meter, so that excessive pressures are not developed in the pressure chamber 21.

The operation of the water-flow meter is illustrated in Fig. 1, wherein the full-line curve indicates the relation which exists between the pressure in the pressure chamber 21 and the rate of flow of the water passing through the meter. It will be noted, that, at the normal or expected rate of water flow, as controlled by the valve 17 and indicated at 32 in Fig. 1, the flow of the water through the meter at a restricted rate develops a pressure of five pounds per square inch in the pressure chamber, which is only one-tenth of the pressure in the water supply main 16. However, if the water flow increases to a value just beyond the point 32, as indicated at 33, the by-pass passage 29 opens and the sensitivity of the meter changes abruptly, as indicated by the difference in the slopes of the lines 34 and 35 of the curve. The dotted line 36 indicates the rapid rise in pressure which would be obtained if the by-pass passage 29 were not provided.

The mercury-vapor pump 13 is also provided with an electric heating element 38 and with a thermostatic contactor device 39 of any desired construction, said thermostat element being placed in any one of several effective positions, whereby it responds to temperature conditions within the pump and gives a reliable indication of the operativeness of the pump.

The operation of the pump is indicated by the curves shown in Fig. 3. When the heating element 38 is first energized, it takes the pump about three-quarters of an hour to heat up to the point wherein it will operate against the pressure of the order of from 1 to 5 or 10 millimeters of mercury existing in the exhaust pipe 14 of the pump, which is connected to the interstage reservoir (not shown). The vacuum valve 9 must remain closed all during said time-interval while the pump is heating. To provide a time-delay switch, which would give satisfactory operation at such extremely long time delays,

would be very costly and unsatisfactory from other considerations. Heretofore, it has been necessary to provide intricate and not altogether satisfactory high-vacuum measuring devices in the intake passage of the mercury-vapor pump, or, more commonly, to do without the protection of any such devices. In my device, by the simple expedient of utilizing a thermal-responsive contactor 39, I have provided a simple expedient for responding accurately to the operative condition of the pump.

In Fig. 3, the heating and cooling curves of the pump are shown, indicating the relations existing between the temperature at the thermostat 39 and the time in minutes after the energization or deenergization of the heating element 38. If the pump begins to be operative at a point 42 on the heating curve 43, the thermostat 39 is set to close its contacts at a slightly higher temperature, whereby a circuit 44 is energized for actuating the operating mechanism of the vacuum-pump 9, as will be subsequently described. If, during the cooling of the pump after the deenergization of the heating means 38, the pump begins to become ineffective at the point 45 of the cooling curve 46, the thermostatic contacts 39 are opened at a somewhat higher temperature, so that the vacuum-valve 9 will be altogether closed before the critical temperature 45 is reached, or, more commonly, the control circuit 44 will be opened as soon as the heater circuit is deenergized, as will be subsequently described.

The valve-operating mechanism consists of a pivotally mounted segmental member 47 having a cam surface 48 of varying radii, for pressing against the top of the valve stem 12 in order to close the valve against the action of a spring 49 surrounding the valve stem. The segmental cam member 47 is yieldably pressed in a valve-closing direction by means of a spring 50, whereby the valve is normally held tightly closed, except when means are provided for opening the same and holding it open.

The valve-opening means consists of a segmental worm-gear member 51, which is mounted on the cam shaft 52, and which is driven by a pivotally mounted worm shaft 53 which carries a worm 54 and which is pivotally mounted at one end to oscillate around a motor shaft 55, to which the worm shaft 53 is connected by means of a bevel gear 56, the motor shaft 55 being driven by an electric motor 57. It will thus be evident that the driving shaft 55 of the motor is parallel to the cam shaft 52, and that the worm shaft 53 is at right angles to the motor shaft and is movable so that the worm 54 moves into and out of engagement with the worm-gear segment 51.

The worm shaft 53 normally falls to a position out of engagement with the segmental

gear 51 and is adapted to be moved into meshing engagement therewith by means of an electromagnet 58 which is energized from the control circuit 44 leading from the thermostatic contactor 39 hereinabove described. The motor 57 is also energized from the control circuit 44, but through the mediation of a limit switch 59 in the shape of a contactor segment carried by the segmental members 47 and 51 and having a dead spot or insulated portion 60 which opens a circuit of the motor 57 when the valve is in its fully opened position, as indicated in the drawings.

54 immediately drops out of engagement with the gear segment 51 and the closing spring 50 instantaneously closes the vacuum valve 9 with a snap action, so that the vacuum valve is fully closed before the mercury-vapor pump 70 becomes inoperative at the point 45 in Fig. 3, indicated as being some ten minutes later. If the heater 38 should burn out while the water-relay 24 is still closed, the control circuit 44 would still be open-circuited by the 75 thermostat 39 before the pump had cooled to the critical point 45 in Fig. 3, as hereinabove described.

The operation of my apparatus will now be readily understood. As long as there is no water flowing in the cooling circuit of the mercury pump 13, or if the water-flow is not sufficient to develop five pounds pressure in the water-flow meter 20, the electrical switch 20 24, associated therewith, is open and no part of my apparatus may be energized. The worm 54 is therefore out of contact with the gear segment 51 and the valve is drawn and held to its closed position by means of the 25 spring 50 pulling on the cam segment 47. The pump heater 38 is also deenergized so that the pump cannot be ruined by operation without any cooling water.

When the proper amount of cooling water 30 flows through the water-flow relay 20, the switch contacts 24 are closed, thereby energizing the pump heater 38 from a suitable supply line such as the 110-volt line 61. After a certain interval, which is indicated 35 in Fig. 3 as being about 45 minutes, when the mercury-vapor pump 13 is in an operative condition, the thermostatic switch-contacts 39 close, thereby energizing the control circuit 44 which energizes the electromagnet 40 58 and also initiates the movement of the motor 57, it being noted that the cam switch 59 is in the dotted-line position indicated in Fig. 2 when the valve is closed, so that the dead point 60 is not under the stationary 45 contactor associated therewith. The energization of the electromagnet 58 draws the worm 54 into engagement with the worm-gear segment 51 and the rotation of the motor 57 drives the worm in a direction such as 50 to open the valve 9, moving the cam segment 47 against the tension of the closing spring 50.

When the valve is fully opened, the dead point 60 of the segmental switch 59 open-circuits the motor 57, but the electromagnet 58 55 remains energized, so that the segmental members are prevented from moving back to switch-closing position by means of the worm 54 which is a non-reversible gear mechanism.

60 The electromagnet 58 remains energized as long as the mercury-vapor pump 13 is in an operative condition. Upon failure of the cooling-water circuit, the switch 24 opens, thereby deenergizing the control circuit 44 65 of the electromagnet 58, whereupon the worm

In the particular embodiment of my invention shown in the drawing, I have contemplated that the mercury-vapor pump shall be normally working all the time, intermittent pumping action being obtained by the intermittent action of the rotary pump (not shown) to pump out the interstage reservoir (not shown) when its pressure becomes too great, as set forth in a copending application of Vladimir K. Zworykin and myself, filed Aug. 3, 1927, Serial No. 210,275.

90 Referring now to the structural details shown in Fig. 4, I preferably provide a compression spring 62 for positively actuating the worm shaft 53 toward its disengaged position. The lower end of the spring bears 95 against a horizontal flange 63 on the bearing member 64 which supports the worm shaft 53, and the upper end of the spring bears against a nut 65 on a link member 66 passing through the compression spring 62 and 100 also through a perforation 67 in the flange or shoulder member 63.

The upper end of the link member 66 is pivotally supported at 68 from the segmental members 47 and 51 in such manner that when 105 the valve is in its fully open position, as indicated by full lines on the drawing, the spring 62 is tightly compressed so that the worm shaft 53 is strongly pressed toward its unmeshed position, whereas, when the valve 110 is closed, as indicated by dotted lines, the pivotal point 68 is moved upwardly so that the pressure of the compression spring is very much reduced, the pressure being preferably entirely removed and the spring being idle in the closed position of the valve.

115 The object of the construction just described is to facilitate the operation of the electromagnet 58, which pulls upon an extension arm 69 of the frame 64 supporting the 120 worm shaft 53, the magnet armature being so pivoted that it presses upwardly on the extension arm 69 when the magnet is energized. As the pulling force of the magnet is much less at the beginning of the movement of its armature than at the end, the reduced pressure of the compression spring 52 makes it possible to utilize a smaller magnet 58 than would otherwise be necessary, and yet the increased compression of the 125 130

spring 62 in the final open position of the valve is not sufficient to overcome the pull of the magnet on its armature when the magnet is in its fully closed position as indicated 5 in full lines on the drawing.

While I have described my invention in a preferred embodiment, I do not wish to be limited altogether thereto, as many changes will occur to those skilled in the art, where- 10 by the essential advantages of my invention may be incorporated in slightly different apparatus. I desire, therefore, that the description and drawings be considered as 15 illustrative only, and that the appended claims shall be given the broadest construction consistent with their language and the prior art.

I claim as my invention:

1. In a vacuum-pumping system, the combination with a chamber to be evacuated, of a mercury-vapor pump, heating means for said pump, means for circulating a cooling fluid around said pump, pipe connections including a valve between said chamber and 25 said pump, mechanical mechanism operable, when actuated, to open and close said valve, thermal responsive means on said pump for actuating said mechanical mechanism to open and close said valve, and means oper- 30 able in accordance with the flow of said cool- ing fluid for controlling said heating means for the pump.

2. In a vacuum-pumping system, the combination with a chamber to be evacuated, of a 35 mercury-vapor pump, heating means for said pump, means for circulating a cooling fluid around said pump, pipe connections including a valve between said chamber and said pump, mechanical mechanism operable 40 when actuated, to open and close said valve, and thermal responsive means on said pump for actuating said mechanical mechanism to open and close said valve.

3. In a vacuum-pumping system, the combination with a chamber to be evacuated, of a mercury-vapor pump, heating means for said pump, means for circulating a cooling fluid around said pump, pipe connections including a valve between said chamber and 50 said pump, mechanical mechanism operable, when actuated, to open and close said valve, and thermal responsive means on said pump for actuating said mechanical mechanism to open said valve.

4. In a vacuum-pumping system, the combination with a chamber to be evacuated, of a pump which develops the necessary vacuum only after a time interval of more than several minutes after the energization of the 55 pump, pipe connections including a valve between said chamber and said pump, mechanical mechanism operable, when actuated, to open and close said valve, and thermal responsive means associated with said 60 pump to operate only after the necessary 65

time interval to actuate said mechanical mechanism to open said valve.

5. In a vacuum-pumping system, the combination with a chamber to be evacuated, a pump, pipe connections including a valve be- 70 tween said chamber and said pump, yieldable means for closing said valve, a motor and non-reversible gear mechanism for opening said valve and holding it in open position against the pressure of said yieldable means, 75 and means for disconnecting said non-re- versible gear mechanism from said valve to permit said yieldable means to close said valve.

6. In a vacuum-pumping system, the combination with a chamber to be evacuated, a pump, pipe connections including a valve be- 80 tween said chamber and said pump, yieldable means for closing said valve, a motor and non-reversible gear mechanism for opening 85 said valve and holding it in open position against the pressure of said yieldable means, means for disconnecting said non-reversible gear mechanism from said valve to permit said yieldable means to close said valve, 90 means responsive to proper operating conditions of said pump to engage said gear mech- anism and initiate the actuation of said motor, and means responsive to a failure or in- 95 terruption of said pump to disengage said gear mechanism.

7. In a vacuum-pumping system, the combination with a chamber to be evacuated, of a mercury-vapor pump, heating means for 10 said pump, means for circulating a cooling fluid around said pump, pipe connections including a valve between said chamber and said pump, yieldable means for closing said valve, a motor and non-reversible gear mech- 10: anism for opening said valve and holding it in open position against the pressure of said yieldable means, means for disconnecting said non-reversible gear mechanism from 10: said valve to permit said yieldable means to close said valve, means responsive to the at- 11: tainment of sufficiently high temperatures in said pump to engage said gear mechanism and initiate the actuation of said motor, and means responsive to a failure or interruption of said pump to disengage said gear mech- 11: anism.

8. In a vacuum-pumping system, the combination with a chamber to be evacuated, of a mercury-vapor pump, heating means for said pump, means for circulating a cooling fluid around said pump, pipe connections includ- 12: ing a valve between said chamber and said pump, yieldable means for closing said valve, a motor and non-reversible gear mechanism for opening said valve and holding it in open position against the pressure of said yield- 12: able means, means for disconnecting said non-reversible gear mechanism from said valve to permit said yieldable means to close said valve, and thermal-responsive means on 13

said pump to engage said gear mechanism and initiate the actuation of said motor in one position, and to disengage said gear mechanism in another position.

5 9. The combination with a valve, of yieldable means for closing said valve, a motor and non-reversible gear mechanism for opening said valve and holding it in open position against the pressure of said yieldable means, and means for disconnecting said non-reversible gear mechanism from said valve to permit said yieldable means to close said valve.

10 10. The combination with a valve, of quick-acting yieldable means for actuating said valve to one position, slow-acting means for actuating said valve to another position and holding it against the pressure of said yieldable means, said slow-acting means comprising a motor and non-reversible gear mechanism, and means for disconnecting said non-reversible gear mechanism from said valve to permit said yieldable means to actuate the same.

11 11. A mechanically actuated valve mechanism characterized by having a cam for pressing the valve to closed position, yieldable means for moving said cam in a valve-closing direction, a motor-actuated non-reversible gear mechanism for moving said cam in a valve-opening direction against the pressure of said yieldable means and for holding the same in said position, and means for uncoupling said non-reversible gear mechanism from said cam to permit the same to move in a valve-closing direction.

12 12. A mechanically actuated valve mechanism, characterized by having a rotatably mounted segment having a cam surface of varying radii for pressing the valve to closed position, yieldable means for moving said cam in a valve-closing direction, a worm-gear segment fixed to the cam shaft, a driving shaft parallel to the cam shaft, a worm shaft disposed at right angles to said driving shaft and carrying a worm, means for pivotally mounting said worm shaft with respect to said driving shaft whereby said worm moves into and out of mesh with said worm-gear segment, a mechanical connection between said shafts, and actuating mechanism for pivotally moving said worm shaft.

13 13. A mechanically actuated valve mechanism, characterized by having a rotatably mounted segment having a cam surface of varying radii for pressing the valve to closed position, yieldable means for moving said cam in a valve-closing direction, a worm-gear segment fixed to the cam shaft, a driving shaft parallel to the cam shaft, a worm shaft disposed at right angles to said driving shaft and carrying a worm, means for pivotally mounting said worm shaft with respect to said driving shaft whereby said worm moves into and out of mesh with said worm-gear segment, a mechanical connection between

said shafts, the driving action of said driving shaft being in such direction as to move said cam in a valve-opening direction, an electromagnet for pivotally moving said worm shaft to engagement with said worm-gear segment, and a spring for pivotally moving said worm shaft out of engagement with said worm-gear segment, the mounting of said spring being such that the movement of the cam in the valve-closing direction reduces the pressure exerted on the worm shaft by said spring.

14 14. A mechanically actuated valve mechanism, characterized by having a rotatably mounted segment having a cam surface of varying radii for pressing the valve to closed position, yieldable means for moving said cam in a valve-closing direction, a worm-gear segment fixed to the cam shaft, a driving shaft parallel to the cam shaft, a worm shaft disposed at right angles to said driving shaft and carrying a worm, means for pivotally mounting said worm shaft with respect to said driving shaft whereby said worm moves into and out of mesh with said worm-gear segment, a mechanical connection between said shafts, the driving action of said driving shaft being in such direction as to move said cam in a valve-opening direction, an electromagnet for pivotally moving said worm shaft to engagement with said worm-gear segment, a spring for pivotally moving said worm shaft out of engagement with said worm-gear segment, the mounting of said spring being such that the movement of the cam in the valve-closing direction reduces the pressure exerted on the worm shaft by said spring, means for simultaneously supplying driving power to said driving shaft and energizing said electromagnet, an electric circuit-interrupting means carried by said cam segment for stopping said driving shaft in the open-valve position of the cam, and means for de-energizing said electromagnet whereby the valve is quickly closed by said yieldable means connected to said cam.

15 15. In a vacuum-pumping system, the combination with a chamber to be evacuated, of a mercury-vapor pump, heating means for said pump, means for circulating a cooling fluid around said pump, pipe connections including a valve between said chamber and said pump, and fluid-pressure-responsive means in the path or circuit of said cooling fluid for controlling said heating means for the pump.

16 16. The combination with a machine to be cooled, of a source of cooling-liquid supply, means including a liquid-flow-restricting feeding valve for connecting said liquid-supply source to said machine, a discharge passage for the liquid leaving the machine, mechanism operable in accordance with the liquid flow disposed in said discharge passage and including a movable diaphragm which is movable inwardly and outwardly in accordance with changes in the said liquid-flow.

mechanism having a restricted orifice through which the liquid flows and develops a pressure head which is a small fraction of the pressure head which would be developed by the liquid-
5 flow through said restricted orifice if said feeding valve were opened wide, a control means actuated by the outward movement of said diaphragm at a predetermined critical pressure developed by a desired restricted
10 rate of flow, and a means operative at, or slightly beyond, said critical pressure for providing for a substantially unrestricted flow of liquid through said mechanism, whereby said diaphragm is protected from excessive pres-
15 sures.

17. In a vacuum-pumping system, the combination with a chamber to be evacuated, of a mercury-vapor pump, heating means for said pump, a source of cooling-liquid supply, 20 means including a liquid-flow-restricting feeding valve for connecting said liquid-supply source to said pump, a discharge passage for the liquid leaving said pump, a mechanism operable in accordance with the liquid flow 25 disposed in said discharge passage and including a movable diaphragm which is movable inwardly and outwardly in accordance with changes in the liquid flow, said mechanism having a restricted orifice through 30 which the liquid flows and develops a pressure head which is a small fraction of the pressure head which would be developed by the liquid-flow through said restricted

orifice if said feeding valve were opened wide, a control means for controlling the energi- 35 zation of said pump-heating means in accordance with said liquid-flow, said control means being operatively associated with said diaphragm to be operated by the outward movement thereof at a predetermined critical 40 pressure developed by a desired restricted rate of flow, and a means operative at, or slightly beyond, said critical pressure for providing for a substantially unrestricted flow of liquid through said mechanism, whereby 45 said diaphragm is protected from excessive pressures.

18. A mechanism operable in accordance with liquid flow and including a movable dia- 50 phragm which is movable inwardly and out- wardly in accordance with changes in the liquid-flow, said mechanism having a re- 55 stricted orifice through which the liquid flows and develops a pressure head, a control means actuated by the outward movement of said dia- phragm at a predetermined critical pres- 60 sure developed by a desired restricted rate of flow, and a means operative at, or slightly beyond, said critical pressure for providing a substantially unrestricted flow of liquid through said mechanism, whereby said dia- phragm is protected from excessive pressures.

In testimony whereof, I have hereunto subscribed my name this 7th day of July, 1927.

ERROL B. SHAND.
